CLAIM

The ornamental design for an antenna housing for an electronic article surveillance system, as shown and described.

DESCRIPTION

FIG. 1 is a perspective view of an antenna housing for an electronic article surveillance system, showing our new design;

FIG. 2 is a side elevational view thereof;

FIG. 3 is an end elevational view thereof;

FIG. 4 is a top plan view thereof.

The broken line disclosure included in FIGS. 1-3 is for illustrative purposes only and forms no part of the claimed design.

FIG. 4

FIG. 1

FIG. 2

FIG. 3
